US00D905471S

(12) **United States Design Patent** (10) **Patent No.:** **US D905,471 S**
Ou (45) **Date of Patent:** **** Dec. 22, 2020**

(54) **PILLOW**

(71) Applicant: **SHENZHEN YOUMIOU TECHNOLOGY CO., LTD**, Shenzhen (CN)

(72) Inventor: **Jixiang Ou**, Ganzhou (CN)

(73) Assignee: **SHENZHEN YOUMIOU TECHNOLOGY CO., LTD**, Shenzhen (CN)

(**) Term: **15 Years**

(21) Appl. No.: **29/727,440**

(22) Filed: **Mar. 11, 2020**

(51) LOC (12) Cl. **06-09**

(52) U.S. Cl.

USPC **D6/601**

(58) **Field of Classification Search**

USPC D6/333, 349, 355, 375, 388, 512, 563, D6/564, 595, 596, 601, 603, 605, 608, D6/604, 611; D24/183–185, 234; D21/803, 804, 805, 809; 5/401, 420, 5/600, 630, 631, 632, 633, 635, 636, 638, 5/639, 646, 652, 652.1, 655, 703, 730, 5/411, 705

Primary Examiner — Sanjeev Paul

(57) **CLAIM**

The ornamental design for a pillow, as shown and described.

DESCRIPTION

FIG. 1 is a perspective view of a pillow showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view thereof.

1 Claim, 9 Drawing Sheets
